UNITED STATES PATENT OFFICE.

LEANDER G. GILBERT, OF BUFFALO, NEW YORK, ASSIGNOR OF ONE-HALF
TO TOBIAS WITMER, JR., OF SAME PLACE.

CAR-HEATER.

SPECIFICATION forming part of Letters Patent No. 394,354, dated December 11, 1888.

Application filed March 26, 1888. Serial No. 268,482. (No model.)

To all whom it may concern:

Be it known that I, LEANDER G. GILBERT, of the city of Buffalo, in the county of Erie and State of New York, have invented new and useful Improvements in Car-Heaters, of which the following is a specification.

This invention relates to that class of car-heaters which are provided with a hot-water boiler and radiating-pipes, whereby the hot water is circulated through the car, and more particularly to an improvement in the heater described and shown in Letters Patent of the United States No. 377,934, dated February 14, 1888. In the heater of this patent an annular water-chamber or boiler surrounds the fire-pot and flame-passage, and the latter is movably arranged upon the fire-pot and provided with means whereby the joint between the flame-chamber and fire-pot is automatically broken in case of an accident to the car, thereby admitting the water in the boiler to the fire-pot and extinguishing the fire. A portion of the water entering the fire-pot is converted into steam, and the expansive force of the latter expels a portion of the water through the chimney; but as the latter is too small to allow all of the water and steam to escape a portion thereof passes through the grate into the ash-pit, and from the latter into the car through the ash-pit door, which is objectionable.

The object of my invention is to improve the construction of the heater, so as to avoid this objection; and the invention consists of the improvements which will be hereinafter fully described, and pointed out in the claims.

In the accompanying drawings, Figure 1 is a sectional elevation of my improved car-heater and one end of a railway-car. Fig. 2 is a side elevation of the heater. Fig. 3 is a sectional elevation of the upper portion of the heater with the actuating mechanism removed.

Like letters of reference refer to like parts in the several figures.

A represents the outer inclosing-shell or boiler of the heater, which is rigidly secured to the floor of the car.

A' is the fire-box or combustion-chamber, arranged in the lower portion thereof, and

having a fuel-door, a, and A² is the grate arranged in the fire-box. The fire-box A' extends through an opening formed in the floor of the car, and is open at its lower end, so that the contents of the fire-box can be discharged directly upon the ground.

B represents a series of vertical tubes or flues arranged within the boiler A, and extending from the fire-box A' to a smoke box or chamber, B', arranged at the upper end of the boiler.

b is the smoke-pipe or chimney connected with the smoke-box B', and extending through the roof of the car.

c represents the feed-pipe of the boiler A, whereby the water is introduced into the boiler from a tank arranged in the car, or from any other source of supply, and c' are the radiating-pipes connected with the boiler A, and through which hot water is circulated through the car.

The fire-box A' is provided in its top with an inlet opening or pipe, D, which is closed by a vertically-movable cap or tube, E, so that by raising said tube from the pipe D the water in the boiler A will be admitted to the fire-box A' and the fire be extinguished. The top of the inlet-pipe D is provided with an annular groove or recess, d, into which the bottom of the cap or tube E fits, and a packing of asbestos is arranged in the recess d, so as to form a tight joint between the lower end of the tube E and the inlet-pipe D. The upper end of the tube E extends through a central opening formed in the top of the boiler A and the smoke-box B', and a stuffing-box, f, surrounds the tube on the upper side of the smoke-box. The stuffing-box f is provided with a packing of asbestos, so as to form a tight joint. The tube E is provided below the stuffing-box f with a partition or diaphragm, g, so as to prevent the heat from rising in the tube and affecting the packing of the stuffing-box.

H is a horizontal plate formed on or secured to the upper end of the tube E, and h is a horizontal shaft journaled in suitable bearings secured to the upper side of said plate.

I I represent flanged pulleys secured to the ends of the shaft h, and i i are chains or ca-

bles fastened at one end to the pulleys I I and at their opposite end to an arm or projection secured to the outer side of the boiler A. The shaft *h* is provided at one end with a detachable crank, *h'*, for turning it.

J J represent elliptical springs arranged on opposite sides of the tube E and interposed between the under side of the horizontal plate H and the gland *f'* of the stuffing-box *f*. These springs tend to raise the plate H and tube E when the shaft *h* is released, and thereby break the connection between said tube and the inlet-pipe D. The springs J J also serve to force the gland *f'* into its seat in the stuffing-box, and thereby maintain a tight joint at this point at all times.

K represents a ratchet-wheel secured to the shaft *h*, and *k* is a pawl pivoted to an arm, *k'*, secured to the plate H and engaging with a ratchet-wheel, K.

L represents a depending weighted lever mounted loosely on the shaft *h*, so as to swing thereon. The lever L is provided with a short arm, *l*, which engages against a V-shaped projection or lug, *m*, formed on the pawl *k*. Upon turning the shaft *h* in the proper direction by means of the crank *h'* the cables *i* are wound upon the pulleys I I, the plate H and tube E are depressed, so as to seat the lower end of the latter firmly upon the inlet-pipe D of the fire-box, and the springs J J are compressed. The parts are now in position for use, and are held in place by the pawl *k* engaging with the ratchet-wheel K. When the car assumes an abnormal position in case of an accident to the train, the upsetting or tilting of the car causes the lever L to swing upon its pivot, and its arm *l*, engaging against the projection *m* of the pawl *k*, lifts the latter out of engagement with the ratchet-wheel K. This movement releases the shaft *h* and cables *i*, and the springs J J now force the plate H and tube E upwardly and break the joint between the tube and the inlet-pipe D of the fire-box, thereby permitting the water in the boiler to enter the fire-pot and extinguishing the fire. A portion of the water and steam escapes into the chimney through the flues B and smoke-box B', while the remaining portion thereof passes through the grate A² and escapes through the open bottom of the fire-box. By this construction of the fire-box the steam generated in the fire-box, when the water enters the same, finds a free vent through the open bottom of the fire-box, thereby preventing a portion of the contents of the fire-box from being forced into the car and injuring the passengers.

N represents a circular plate journaled in the lower open end of the fire-box below the grate A², and which forms a damper for regulating the draft to the fire-box, and also serves as a movable bottom for closing the lower end of the fire-box and preventing cinders from dropping out of the fire-box when the car stands in a depot or other place which is liable

to take fire. The damper N is provided with a number of perforations, as shown, so as to admit air to the fire-box when the damper is entirely closed, the perforations being so small as to retain the cinders. One of the pivots or journals of the damper N is provided with a crank, *n*, which is connected to the lower end of an adjusting-rod, *o*, extending upwardly through an opening in the car-floor.

o is an adjustable collar secured to the rod *o*, and which is adapted to bear against the floor of the car, so as to hold the damper in any desired position. By raising or lowering this collar on the rod *o* the damper can be closed to a greater or less extent.

p represents a rod pivoted at its upper end to the shaft *h*, and provided at its lower end with a link, *p'*, in which is arranged a pin, *p²*, secured to the upper end of the rod *o*. The link *p'* is of sufficient length to permit the rod to be raised and lowered on the same for adjusting the damper without disturbing the position of the rod *p*. When the shaft *h* is released and elevated in case of an accident, the rod *p* is also drawn upwardly, thereby raising the lower rod, *o*, by means of the pin *p²* and opening the damper N. In this manner the damper is automatically opened at the same time that the water is discharged into the fire-pot, thus leaving the bottom of the fire-pot unobstructed and allowing the steam and water to escape therefrom.

I claim as my invention—

1. The combination, with the boiler A, provided with a smoke-box, B', of the fire-box A', arranged within the same and provided with an open bottom and with an inlet-opening in its top, a movable cap or tube, E, closing said opening, and flues B, connecting the fire-box with the smoke-box, substantially as set forth.

2. The combination, with the boiler A, provided with a smoke-box, B', and a central opening extending through the top of the boiler and the smoke-box, of a fire-pot arranged within the boiler below the smoke-box and provided with an inlet-tube, D, in its top, a movable tube, E, extending through the central opening in the boiler and smoke-box and resting with its lower end upon the tube D, a stuffing-box, *f*, surrounding the tube E, a plate, H, secured to the tube E above the stuffing-box, and springs J, interposed between the plate H and the gland of the stuffing-box, substantially as set forth.

3. The combination, with the boiler A and fire-box A', having an open bottom and provided in its top with an inlet-pipe, D, of a movable cap or tube, E, closing said inlet-pipe and provided with a plate, H, a damper or pivoted plate, N, arranged in the open bottom of the fire-box, and a connecting-rod and crank, whereby said damper is operated from the plate H, substantially as set forth.

4. The combination, with the fire-box having the inlet-pipe D and made open in its bottom, of a damper, N, arranged in the open bot-

tom of the fire-box and provided with a crank, the tube or cap E, closing the pipe D and provided with a plate, H, a shaft, *h*, mounted on said plate and provided with drums I, having 5 cords *i*, and a ratchet mechanism, K *k*; a depending lever, L, pivoted to said shaft, a rod, *p*, attached to the shaft *h* and provided in its lower end with a link, and a rod, *o*, pivoted to the crank of the damper N and provided with a pin engaging in said link, substantially as 10 set forth.

Witness my hand this 20th day of March, 1888.

LEANDER G. GILBERT.
